UNITED STATES PATENT OFFICE.

JAMES P. QUINN, OF CHICAGO, ILLINOIS.

WINDOW-SCREEN.

1,167,929.

Specification of Letters Patent.

Patented Jan. 11, 1916.

Application filed August 22, 1914. Serial No. 858,083.

To all whom it may concern:

Be it known that I, JAMES P. QUINN, a citizen of the United States, residing at Chicago, in the county of Cook and State of Illinois, have invented certain new and useful Improvements in Window-Screens, of which the following is a specification.

My invention relates to improvements in screens for windows.

10 One of the general objects of my invention is to provide a screen for permanent association with a window and preferably designed to cover the entire window frame opening, and a housing to contain the 15 screen and protect it from the weather when it is not in actual use.

One of the specific objects of my invention is the provision of sheet metal guide channels of peculiar character for the marginal 20 edge of the wire cloth screen.

Another such object is the provision of selvage binding to cover and protect the raw edges of the screen, and still another object is the provision of folding clips secured to the window sills to hold the screen extended against the tension of a retracting roller spring contained in the housing.

Other and further objects of my invention will be readily understood by persons skilled 30 in the art from a consideration of the following description when taken in conjunction with the drawings, wherein—

Figure 1 is an elevation of a window showing my screen and fixtures in place. 35 Fig. 2 is an enlarged, transverse section taken on line 2—2 of Fig. 1. Fig. 3 is an enlarged elevation of a detail. Fig. 4 is an enlarged, transverse section taken on line 4—4 of Fig. 1. Fig. 5 is an enlarged transverse section taken on line 5—5 of Fig. 1. Fig. 6 is a perspective view of the folding latch for holding the screen in extended position.

In all the views the same reference characters are employed to indicate similar parts.

10 represents the outside of a house showing a window frame composed of the stiles 11—11, the sill 12 and the lintel 13, common in such structures. The window sashes 14 and 15 slide vertically within the casing or frame as usual. Fig. 1 shows both of the window sashes 14 and 15, pulled down from the top near to the sill.

My screen 16 is composed of suitable wire cloth that may be employed for the pur-

pose. One end of the screen is secured to a spring impelled roller 17, as at 18. The roller is of the same general character as that used for window shades, with the exception that the latch dogs used for arresting the operation of the spring are preferably not employed. The roller is supported in a housing 18, at each end thereof, and the ends of the housing are provided with base portions 19, through which screws or nails 20 may pass to secure the device to the window frame. An arcuate shutter or door 21 may be provided in the housing having a knob 22 by which it may be raised or lowered and when in raised position, as shown 25 in Fig. 2, the roller 17 with the wire screen contained thereon, may be removed from the housing, and when the roller has been placed in the housing the shutter 21 is pulled down so as to protect the contents 30 from the corroding effects of the weather.

On the inside of the vertical stiles of the window frame are provided guide-ways 24—24, made preferably of sheet copper and initially in the U shape shown in dotted lines, as at 25, in Fig. 3, at which time the securing nails 26 are placed in the base part 24' on either side of a transverse center and longitudinally of the strip. After the nails have been placed in the U shaped structure 35 the sides 25—25 may be bent inwardly, as shown at 25' toward the axis of the guide so that the longitudinal edges of these parts may more closely approximate the surfaces or marginal binding of the screen 16. The 40 nails 26 being placed on either side of the transverse central plane the screen 16 may be freely moved within the channel guide-ways thus provided, without interference from the nails. The longitudinal selvage edge of 45 the screen 16 may be bound with cloth or other fabric or material 27, as by stitching, so as to protect the edges of the screen cloth and to make better contact with the edges of the parts 25 to prevent entrance of 50 insects, such as flies, mosquitos and the like into the room. The strengthening bar 28 is placed across the bottom of the screen and secured thereto by suitable means. A guide roller 30 may be placed transversely of the 55 window frame to guide the screen cloth 16 into the channels 24—24 so that the screen may be moved vertically in the channels without undue binding at any point.

One or more rotatable eyes 31—31 may be 60

2

secured to the cross bar 28 and serve, in connection with a coöperating latch member secured to the sill 12, as a means for holding the screen in its extended position. In the 5 specific exemplification two such members are shown, one near each of the edges of the screen and two coöperating folding latch members 32—32 are also shown secured to the sill. The latch is provided with a blade 10 33 which is perforated, as at 34, for entrance of the eye 31. It is hinged to a blade 35, as at 36, the blade 35 being secured to the sill 12, as by screws taking through the holes or 15 perforations 37. A cord 38 may be secured to the cross bar 28 as a means for lowering or pulling down the screen, against the effect of the spring 17' contained within the roller 17. After the screen has been lowered, in 20 the manner described, the blade 33 of the clip 32 is raised and the eye 31 is passed through the perforation 34 as shown in Fig. 5, after which the eye 31 may then be turned about 90 degrees, which will serve to hold the screen in its extended position. When 25 the screen is rolled up out of the way, the blade 33 may be folded back on the blade 35 and thereby it will be caused to occupy a very small space. When the screen has been lowered and secured in extended position 30 there is not a space left through which an insect may enter the room, which is guarded by the screen, and when the screen is up in

its contracted position it will be substantially contained within the housing 18.

While I have herein shown a single embodiment of my invention for the purpose of clear disclosure, it is evident that considerable changes may be made in the sizes and dispositions of the parts, without departing from the spirit and scope of the appended 40 claim.

Having described my invention, what I claim is:—

In a window screen structure, a roller supporting and inclosing housing comprising 45 end members, a cover piece extending from end to end, curved downwardly at its outer edge and terminating approximately in a plane passing horizontally through the axis 50 of the roller, means carried by the end members for supporting the roller within the housing, and a shutter curved to conform to the curvature of the cover piece extending from end to end of the housing and slidable 55 up under the cover piece for removal of the roller or down under the roller to partially inclose the same.

In testimony whereof I hereunto set my hand in the presence of two subscribing witnesses.

JAMES P. QUINN.

In the presence of—
FORÉE BAIN,
MARY F. ALLEN.
